UNITED STATES PATENT OFFICE.

FREDERICK W. VODOZ, OF WILMETTE, ILLINOIS, ASSIGNOR TO GOODMAN MANUFACTURING COMPANY, OF CHICAGO, ILLINOIS, A CORPORATION OF ILLINOIS.

CUTTER CHAIN.

Application filed December 24, 1924. Serial No. 757,896.

This invention relates to improvements in cutter chains for kerf cutting mining machines, and more particularly to cutter blocks, and has for its principal object to produce a new and improved block wherein a simple and efficient form of set screw is used for securing the bit in place, the bit projecting from the front face of the cutter block, but means are provided for protecting the projecting portion of the set screw from abrasion, which means also serve to propel the cuttings and clear them from the kerf.

Heretofore many forms of cutter blocks have been devised having more or less complicated clamping devices for the purpose of securing the cutter bit in place. It has been demonstrated that a cutter bit is likely to work loose during the cutting operation. One of the simplest and most efficient means for clamping heretofore used consists of a set screw extending through the front of the block and engaging the cutter bit to force it rearwardly against a relatively flat bearing surface formed by the rear wall of a bit receiving aperture. One objection to this general form of block however, is the fact that the head of the set screw, which projects through the front face of the block, is in the path of the cuttings and therefore is subject to considerable wear and abrasion, which often destroys the shape of the set screw head, so as to render it useless. A further objection to this arrangement is due to the fact that the projecting set screw acts as a wedge to part the cuttings to either side of the block, thus permitting the block to cut through the cuttings instead of carrying them along with the cutter chain, as is most desirable in clearing the cuttings from the kerf.

In my present invention I provide a cutter block utilizing the general and well known form of set screw above described but in conjunction therewith I provide a series of plates or propellers carried by the blocks which protect the set screw head from abrasion and furthermore provide in effect a bearing surface suitable for clearing the cuttings and carrying them with the chain so as to be ejected from the kerf.

My invention may best be understood by reference to the accompanying drawings wherein:

Figure 1 is a side view of a cutter block

and a pair of connecting straps constructed in accordance with my invention;

Figure 2 is a sectional view taken on line 2—2 of Figure 1;

Figure 3 is a sectional view taken on line 3—3 of Figure 1;

Figure 4 is a side view of a portion of cutter arm with a cutter chain including several cutter blocks and bits extending at various angles suitable for cutting the proper width of kerf; and

Figures 5 to 11, both inclusive, are front views of a series of blocks extending in various positions as shown in Figure 4.

Referring now to the details of the cutter chain and blocks shown in the drawings, Figure 1 is a view of a center block 10 in which the cutter bit extends from the center of the block in substantially the same plane as the central plane of the cutter bar. It will be understood that the cutter chain of this character works in a groove formed in any suitable manner about the cutter bar A, being retained therein by means of lips 11, 11, formed along the base of the cutter block and on opposite sides thereof, and similar lips 12, 12, formed on opposite sides of the straps 13, 13. The block 10 has a lower body portion or base 15 restricted to fit within the cutter arm groove and an outer body portion 16 adapted to extend beyond the groove. A pair of holes 17, 17, are provided for connections with the straps 13, 13, in the usual manner. The bit 20 fits in an aperture 21 which in the form shown is inclined forwardly in the block and extends downwardly between the holes 17, 17. The bit may be of any suitable design, as for instance, it may comprise a flat piece which may be of bar stock tool steel sharpened at both ends, so that either end may be used as desired. The bit is secured in place by a set screw 25 threaded through a boss 26 at the front end of the body portion 16 and preferably substantially at right angles to the bit receiving aperture. The head 27 of the set screw projects somewhat beyond the boss 26, in the usual manner. In the position shown it will be noted that the set screw engages the bit to force it firmly against the rear face 29 of the bit-receiving aperture, thus securing the bit firmly in place.

I further provide web shaped projections 30 and 31 on opposite sides of the set screw.

These projections 30 and 31 are preferably integral with the block and extend laterally and then forwardly on opposite sides of the boss 26 to a point substantially in alignment with or beyond the front of the set screw 27 when in normal position as shown. The extreme width of the projections preferably is substantially the total width of the cutter bar as shown in Figure 4, and these projections form in fact a socket opening upwardly and forwardly, as shown. This socket is of sufficient size to permit a socket wrench to be inserted therein for engagement with the head of the set screw. Variations in the size and position of the lateral projections are desirable, depending upon the angle of incidence of the cutter bit and bit holder to the cutter bar, as illustrated in various forms shown in detail in Figures 5, 6 and 7, and 9, 10 and 11. For instance in the form shown in Figure 7, in which the bit and holding portion 16 are inclined slightly to the left, the right hand projection 30^a is in substantial longitudinal alignment with the similar projection 30 on the center block shown in Figures 1 to 3, and Figure 8. The left hand projection 31^a however is not as high as the corresponding left hand projection 31 in the center block. The arrangement is such that the top end of the left hand projection in connection with the top of the right hand projection is sufficient to form a substantial barrier to the passage of cuttings and also protects the head of the set screw from abrasion. Figure 9 is the same form of block as in Figure 7 but with the cutter bit and block body inclined to the right instead of to the left. Figures 6 and 10 are similar to the forms shown in Figures 7 and 9 but with the bits inclined somewhat more from the perpendicular. Figures 5 and 11 show the extreme positions of the cutter bit and block. In these positions it will be observed that the web on the extreme side of the block nearest the cutter bit is omitted, so as to permit the use of a socket wrench for adjusting the set screw. In this case however the projections at one side of the block body portion 16 form a sufficient web between the projection and the boss to propel the cuttings and protect the set screw. It will be understood that my invention may be applied to a chain comprising any desired number of bit positions differing from the seven positions on the chain illustrated herewith. While I have shown and described one embodiment of my invention, it will be understood that the arrangement and construction of the various parts may be altered without departing from the spirit and scope of the invention. Furthermore, I do not wish to be construed as limiting myself to

the particular construction illustrated excepting as may be specifically limited in the appended claims.

I claim as my invention:

1. A cutter chain block having a body provided with an outwardly extending bit receiving aperture, a set screw extending through the front face of said block for securing a bit in said aperture, the head of said set screw normally projecting beyond the front face of said block, and cuttings propelling means carried by said block and extending laterally therefrom thence forwardly to form a protection for the head of said set screw. 80

2. A cutter chain block having a body provided with an outwardly extending bit receiving aperture, a set screw extending through the front face of said block for securing a bit in said aperture, the head of said set screw normally projecting beyond the front face of said block, and a cuttings propelling formation formed integrally with said block and extending laterally therefrom adjacent said aperture thence forwardly with a marginal flange portion to form a protection for the head of said set screw. 90

3. A cutter chain block having a body provided with an upwardly extending boss having a correspondingly extending bit aperture therein, a set screw extending through the front face of said boss for securing a bit in said aperture, the head of said screw normally projecting beyond the front face of said block, and a cuttings propelling formation formed integrally with said block and extending laterally from said boss and thence forwardly with a side and bottom marginal flange portion to form a protection for the head of said set screw. 100

4. A cutter chain block having a body provided with an outwardly extending bit receiving aperture inclined laterally from the perpendicular plane of the block, a set screw extending through the front face of said block for securing a bit in said aperture, the head of said set screw normally projecting beyond the front face of said block, and cuttings propelling means carried by said block and extending laterally therefrom on both sides of the same and thence forwardly to form a protection for the head of said set screw, the portion of said cuttings propelling means on the side of said block in the direction of which said aperture inclines being lower than the other portion thereof. 110

5. A cutter chain block having a body provided with an upwardly extending boss inclined laterally from the perpendicular plane of the block and having a correspondingly extending bit aperture therein, a set screw extending through the front face of 120

said boss for securing a bit in said aperture, the head of said set screw normally projecting beyond the front face of said block, and a cuttings propelling formation 10
5 formed integrally with said block and extending laterally from said boss on both sides thereof and thence forwardly with a side and bottom marginal flange portion to form a protection for the head of said set screw, the portion of said cuttings propell- 10
ing formation on the side of said boss in the direction of which the boss inclines being lower than the other portion thereof.

Signed at Chicago, in the county of Cook and State of Illinois, this 20th day of De- 15
cember, A. D. 1924.

FREDERICK W. VODOZ.
